UNITED STATES PATENT OFFICE.

RAYMOND E. CRANE, OF KITTANNING, PENNSYLVANIA.

SANITARY FIXTURE.

Application filed August 17, 1927. Serial No. 213,666.

My invention relates to an attachment for an ordinary closet bowl which provides a stream of water directed approximately horizontally from a point directly above the flushing rim of the bowl at the rear of the top rim opening in such way that it can be used as a bidet.

The objects sought in my invention are to provide an attachment which will be available in connection with a closet bowl that will enable the fixture to serve the additional purposes of a bidet; to accomplish the said object in a manner which will not interfere with the proper cleaning of the upper rim of the bowl and in which the supply nozzle and the other parts of the attachment will not be in the way of such proper cleaning, and to accomplish said objects with a fixture that will be as inconspicuous as possible and which will be swung out of the way when not in use or when the seat cover is lifted.

I attain these objects in the manner shown in the accompanying drawings, in which Figure 1 is a top view of the rear part of a closet bowl showing a seat hinge and bidet valve in place and with the location of the bidet nozzle indicated in its relation to the seat. Figure 2 is a side view partly in section of the device as shown in Figure 1, the upper part of the seat and the hinge being shown in section along the line A—B of Figure 1. Figure 3 illustrates the seat partly raised, the hinge post and the bidet nozzle with the rear part of the seat being shown partly in section. Figure 4 shows a modification of the view shown in Figure 1, and in this instance the bidet nozzle is not directly attached to the seat as in Figure 1 but may be pivoted on the axis of the main bar of the seat hinge (or stationary). Figure 5 shows a vertical view partly in section of the construction shown in Figure 4 along the lines A'—B'.

In many places the bidet is a very common fixture and its installation generally accepted, whereas, in other places such a fixture is either uncommon or there is considerable prejudice in connection with its installation and use. By its simplicity and inconspicuous nature, the fitting made in accordance with my invention will overcome the objections to the use of other types of apparatus. The provision for swinging the jet nozzle up out of the way either by the lifting of the seat, as in Figure 1, or by lifting the nozzle out of the way for the cleaning of the bowl rim, is accomplished in a way which is convenient,

sanitary and at the same time providing a rigid construction because of the short distance between the nozzle and the main bearings supporting the seat hinge.

The construction and operation of the device shown in the attached drawings, in which similar figures refer to similar parts throughout the several views, is as follows:

The closet bowl (1) is furnished with a hinged seat (2), said seat being secured to the bowl (1) by means of a hinge. This hinge is provided with a pair of threaded posts (3—3), which posts pass through shelves made integral with the closet bowl for the purpose of receiving these posts. The seat (2) is provided with arms (4—4) which are secured to the seat and which are mounted on the hollow hinge pindle (7). This hinge pindle (7) is a hollow tube which not only serves as a support for the hinge arms (4—4) to swing on but also serves as a pipe for conducting water to the bidet nozzle (5) which nozzle also revolves on hinge pindle (7), the water connection being made tight by means of stuffing box nuts (6—6). In Figures 1, 2 and 3 the bidet nozzle (5) is securely screwed to seat (2) by means of two screws or the like 11—11. A small hole in the tubular pindle (7) is indicated at 8 for permitting the water supply to pass from tube (7) to nozzle (5).

Ordinary compression control valves are indicated at 10—10 for the purpose of supplying water to nozzle (5). These valves are connected to tube (7) by means of an ordinary union nut 9. A dotted line is shown at 12 to indicate the slightly upwardly direction to which the stream is directed. Experience has shown this slightly upward direction as being particularly well adapted for the purpose of this device.

It will be readily appreciated by those skilled in the art, particularly those who have had both installation and selling experience in the bidet field, that the swinging of the nozzle entirely out of the way when the seat is lifted eliminates the principal objection to the combination bidet attachments, heretofore used, especially where a rigid construction is provided, and furthermore a dual purpose fixture is thus provided at a comparatively small amount of extra cost over the price of a single fixture, as will be readily apparent to one familiar with this type of device.

I am aware that prior to my invention there have been many attempts made to pro-

vide such a dual fixture but the various disadvantages inherent to their construction have interfered with their popularity.

It is to be understood that the practical combination of features shown as in the instant application is capable of various modifications within the scope of the following claims:

1. A sanitary fixture having a seat shelf 10 and basin and being provided with a seat, a hinge by which said seat is attached to said fixture, a discharge nozzle extending forwardly from the seat shelf of the fixture toward the basin thereof, means for connecting 15 the nozzle to swing the same in an upwardly direction so that it will not interfere with the proper cleansing of the fixture, and means for supplying water to said forwardly extending nozzle.
- 20 2. A sanitary fixture including a basin provided with a seat, a hinge for said seat, a nozzle extending forwardly from the rear of said seat and discharging in a line substantially parallel with the seat towards the 25 basin, means for swinging said nozzle in an upward direction and a hollow hinged pintle providing a supply pipe for said nozzle.
3. A sanitary fixture including a basin 30 and a seat, a hinge provided with a hollow pintle for said seat, and a nozzle extending forwardly from the rear of said seat and discharging in a line substantially parallel with the seat towards the basin, said forwardly 35 extending nozzle being secured to and supplied through said hollow pintle.

4. A sanitary fixture including a basin and a seat, a hinge provided with a hollow pintle for attaching said seat to the basin, a discharge nozzle extending forwardly towards the basin and means for pivotally connecting the nozzle to said pintle. 40

5. A sanitary fixture including a basin and a seat, a hinge for said seat, a discharge nozzle extending forwardly from the rear 45 of said seat and substantially horizontal thereto, and means whereby the nozzle is carried by and movable with said seat.

6. A sanitary fixture provided with a seat, a hinge for said seat comprising a supply conduit, a substantially horizontal nozzle opening at the back of the seat and parallel thereto when said seat is in normal position and means for supplying water to the nozzle through said conduit. 50

7. A sanitary fixture including a basin, and a seat, a forwardly and horizontally directed nozzle, said nozzle being substantially parallel with the seat when said seat is in normal position, a conduit fitting extending 60 across the back of said basin and secured thereto, said nozzle being carried directly by said fitting and means for supplying water to the fitting.

8. A sanitary fixture including a basin and a seat having a forwardly directed nozzle parallel with said seat, a hinge for attaching the seat to said basin and means for supplying water to the nozzle through a part of 65 said hinge. 70

In testimony whereof I affix my signature.

RAYMOND E. CRANE.
